(57) **CLAIM**

The ornamental design for a touch screen and support assembly, as shown and described.

DESCRIPTION

FIG. 1 is a perspective view of a touch screen and support assembly, showing our new design.

FIG. 2 is a front, elevation view of the touch screen and support assembly of FIG. 1.

FIG. 3 is a right side elevation view of the touch screen and support assembly of FIG. 1, the left side elevation view being a mirror image of the right side elevation view.

FIG. 4 is a rear, elevation view of the touch screen and support assembly of FIG. 1.

FIG. 5 is a bottom view of the touch screen and support assembly of FIG. 1.

FIG. 6 is a sectional view further illustrating the exterior surface of a portion of the touch screen and support assembly of FIG. 1, taken along line 6-6 shown in FIG. 2.

FIG. 7 is a perspective view of another touch screen and support assembly, showing our new design.

FIG. 8 is a front, elevation view of the touch screen and support assembly of FIG. 7.

FIG. 9 is a right side elevation view of the touch screen and support assembly of FIG. 7, the left side elevation view being a mirror image of the right side elevation view.

FIG. 10 is a rear, elevation view of the touch screen and support assembly of FIG. 7.

FIG. 11 is a bottom view of the touch screen and support assembly of FIG. 7; and,

FIG. 12 is a sectional view further illustrating the exterior surface of a portion of the touch screen and support assembly of FIG. 7, taken along line 12-12 shown in FIG. 8.

The long dash lines shown in FIGS. 1, 2, 4, 7, 8, and 10 immediately above the shaded areas define the boundaries of the claimed portion of the touch screen, while all other lines are directed to environment and form no part of the claimed design.
